UNITED STATES PATENT OFFICE.

FRANK M. WHITING, OF NORTH ATTLEBOROUGH, MASSACHUSETTS.

DESIGN FOR A SPOON.

SPECIFICATION forming part of Design No. 20,826, dated June 9, 1891.

Application filed April 23, 1891. Serial No. 390,176. Term of patent 3½ years.

To all whom it may concern:

Be it known that I, FRANK M. WHITING, a citizen of the United States, residing at North Attleborough, in the county of Bristol and State of Massachusetts, have invented and produced a new and original Design for Spoon-Handles, of which the following is a specification, reference being had to the accompanying drawings, which form a part thereof.

10 My invention is a design for the handles of spoons, forks, and other articles having similar-shaped handles.

In the accompanying drawings a portion of a spoon-handle is shown, showing my design thereon.

15 The design consists of a pictorial representation of the landing of the Pilgrims, and includes a boat shown near the shore, with figures in the boat and on the shore and a vessel in the distance, these illustrations being contained on the upper surface of the

upper or enlarged part of the spoon-handle. This illustration is inclosed by a bead, as a frame, extending from the contracted part of the spoon on the upper part of the illustration around the end of the spoon-handle to the under part of the illustration. Beginning at the contracted part of the spoon-handle and extending toward the enlarged part are the words "Landing of the Pilgrims," followed by 25 the numbers "1620;" but these words and number form no part of my design.

I claim—

The design hereinbefore shown and described, consisting of the representation of 30 the landing of the Pilgrims.

In testimony whereof I affix my signature in presence of two witnesses.

FRANK M. WHITING.

Witnesses:

J. E. POND,
ARTHUR T. PARKER.
